UNITED STATES PATENT OFFICE.

ERNEST E. MINARD, OF DETROIT, MICHIGAN.

FOUR-WAY VALVE.

1,317,211.

Specification of Letters Patent. Patented Sept. 30, 1919.

Application filed December 20, 1918. Serial No. 267,644.

To all whom it may concern:

Be it known that I, ERNEST E. MINARD, a citizen of the United States of America, residing at Detroit, in the county of Wayne and State of Michigan, have invented certain new and useful Improvements in Four-Way Valves, of which the following is a specification, reference being had therein to the accompanying drawings.

10 This is an improvement for that type of four-way valve disclosed in my application filed March 14, 1918, Serial No. 222,290, and allowed Sept. 12, 1918, and wherein is shown a valve for controlling air under pressure, 15 utilized as a motive fluid for producing a reciprocating movement of a piston in a cylinder. The four-way valve was particularly designed for an equipment adapted for shifting the jaws of a chuck or other device, and may be briefly described as comprising a stationary ported body adapted to receive air under pressure; a reservoir carried by said body and adapted to maintain an intermediate pressure, and a rotary 20 valve member carried by the stationary body and ported so that in one position of the valve member there are two air passages therethrough; in another position motive fluid permitted to simultaneously pass 25 through the valve member and also enter the reservoir, and in another position permit of motive fluid simultaneously exhausting from the reservoir and also passing through the rotary valve member. This 30 constructive arrangement of ported parts permitted of an intermediate pressure being maintained in the reservoir to be utilized for shifting the piston, independent of the main supply of air used to maintain chuck jaws 35 open or closed, or the piston in its extreme positions and in this valve I discovered that this intermediate pressure is not at all times sufficient for the purpose for which it is intended. Even though I made provision 40 for increasing and decreasing the capacity of the reservoir, as mentioned in my prior application, I found such means not at all satisfactory particularly from a manufacturing standpoint.

45 The improvement resides in a novel reservoir or reservoir chamber and an automatic valve therein by which an intermediate or working pressure of air can be built up to meet any requirements, such, for instance 50 as greater piston travel and to compensate for leakage. To accomplish this it is only

necessary to use a small reservoir as irrespective of the size of a reservoir the pressure of air therein is never higher than the main line pressure, and a small reservoir 60 for mounting purposes is particularly advantageous in an equipment for a lathe or similar piece of machinery.

The type of valve which I employ is capable of adjustment and presents a greater 65 area to the interior of the reservoir than to the main line pressure of air. This greater area, plus the tension or expansive force of a spring associated with the valve, causes the valve to recede or unseat only 70 when the air pressure in the reservoir chamber drops below a required working pressure, otherwise the reservoir chamber is charged independent of any valve movement. 75

These improvements will be more apparent as the nature of the four-way valve is better understood by hereinafter referring to operating conditions that existed prior to the improvement, but reference will first 80 be had to the drawing, wherein—

Figure 1 is a side elevation of the four-way valve, partly broken away and partly in section, showing my improvement in connection therewith; 85

Fig. 2 is an end view of the four-way valve in its normal position;

Fig. 3 is a cross sectional view of the same, showing the reservoir;

Fig. 4 is a longitudinal sectional view of 90 the valve taken on the line IV—IV of Fig. 2, after the valve is adjusted to its final or extreme position;

Fig. 5 is a similar view showing an intermediate adjusted position of the valve; and, 95

Fig. 6 is an end view of the valve associated with a work cylinder, which is shown in section with the piston therein shifted to maintain the jaws of the chuck closed.

As before stated, the four-way valve comprises a stationary body 1, a reservoir chamber 3 and a rotary valve member 7, the reservoir chamber 3, being suitably connected to one face of the stationary body 1 and constituting a support therefor, while the rotary valve member 7 rotates against the other face of the stationary body 1. 100

In order that the functions of the valve may be understood and particularly the improvement therewith, it is necessary to consider the four-way valve in connection with 110 a work cylinder C, shown in Fig. 6, the

cylinder containing a reciprocable piston D and a piston rod E adapted for shifting chuck jaws either to clamp a piece of work or to release the same. The work cylinder 5 may be considered as having chambers A and B at the sides of the piston D, with said chambers connected by pipes F and G to the stationary body 1 of the valve, so that motive fluid, as air, may be admitted to and 10 exhausted from the chambers of the work cylinder.

The stationary body 1 has an air intake port 11 adapted to communicate with a suitable source of motive fluid, as air under 15 pressure, and said body is also provided with an exhaust port 24 open to the atmosphere. The inner end of the port 11 is open at the front face of the valve body and is adapted to communicate with one end of the 20 curved groove 12^a in the face of the valve body, said groove having its opposite end communicating with a port 16 leading to an angle port 12 in the rotary member 7. The port 12, as well as another angular port 13 25 in the rotary member 7 is formed in two parallel planes, the angle port 12 being adjacent the inner face of the rotary member and the angle port 13 adjacent the outer face thereof, said angle port 13 communicat- 30 ing by a port 19 with a curved groove 13^a in the outer face of the rotary member. To form the ports 12 and 13, the rotary member is provided with bores having the outer ends thereof closed by plugs 14^a.

35 The angle port 12 and its groove 12^a communicate with ports 15, 16, 17 in the face of the rotary member 7, and the angle port 13 and its groove 13^a communicate with ports 18 and 19 in the face of the rotary member.

40 The stationary valve body 1 has a port 41 communicating with the reservoir chamber 3, and the face of the stationary valve body has ports 22 and 23, besides the port 24 previously mentioned. The port 22 communicates with the pipe F and the port 23 with the pipe G.

45 With the stationary valve body 1 and the rotary valve member 7 ported for the passage of air, as set forth above, the following operations are possible, starting with the valve in the position shown in Fig. 2.

The supply of air under pressure entering 50 the port 11 passes through the port 17 and groove 12^a into the angle port 12, then into the port 23 and through the pipe G into chamber A of the work cylinder C. With the pressure of air shifting the piston D to one end of the cylinder, the chamber B exhausts through the pipe F, port 22 into the 55 groove 13^a, angle port 13 and port 24 to the atmosphere. The jaws of the chuck are now maintained closed holding a piece of work and the piston D is in close proximity to the 60 end wall of the cylinder C. This initial ad-

justment of the valve is the same as the original four-way valve, and the reservoir chamber 3 may be charged with air, under pressure, due to previous operations of the valve.

70 Before proceeding with a further adjustment of the valve it is thought best to consider the reservoir chamber, *per se*, shown in Figs. 1, 3 and 4. The reservoir chamber 3 is in the form of an oblong groove or recess in the finished face of a plate 31 suitably connected to the stationary valve body 1. The outer face of the plate 31 has a split sleeve or clamping member 32 which permits of said reservoir chamber and the other parts of the valve being attached to a suitable support 33. The split sleeve 32 has an offset portion 34 provided with a longitudinal bore 35 communicating with the reservoir chamber 3, and the bore 35 has its walls 75 screw threaded to receive an adjustable abutment 36 and a plug 37. The adjustable abutment 36 is engaged by the outer end convolution of a coiled compression spring 38 in the inner end of the bore 35, said spring 80 having other end convolutions thereof encircling the stem 39 of a flat disk-shaped valve 40, which I prefer to term a "pressure building valve". This valve is located at 85 one end of the reservoir chamber 3 and is held normally against the ground face of the stationary valve body 1. In engaging the face of the valve body 1, the valve 40 normally closes a port 41 communicating with the main line pressure port 11, and this 90 port 41 is in addition to the stationary valve body of the original four-way valve.

95 The port 41 is necessarily of less cross-sectional area than the valve 40, consequently the valve 40 presents a greater area 100 in the reservoir chamber 3, than what it does in the port 41. It is this greater valve area that permits of the expansive force of the spring 38 together with the pressure of air 105 in the reservoir chamber 3 maintaining the valve 40 closed against the main line pressure in the ports 11 and 41. So, with the valve 40 normally closed, the initial adjustment of the valve, as previously set forth, can take place independent of the reservoir.

110 Considering the second operation of the valve or its intermediate position preparatory to releasing the pressure of the jaws of the chuck or other device, a handle 8 of the valve is shifted counter-clockwise to a position approximately between thirty and seventy degrees from initial position, and the rotary valve member 7 establishes port communication as shown in Fig. 5. The groove 12^a of angle port 12 will establish communication 115 between the main line air port 11 and the reservoir chamber 3, so that said reservoir chamber may be charged from the port 11 through the ports 17, groove 12^a and port 21, as shown in Fig. 5. Simultaneous with 120

this charging of the reservoir the pressure of air within the chambers A and B of the work cylinder C is equalized by the ports 22 and 23 being placed in communication with each other through the medium of the groove 13^a of the angle port 13. It is therefore apparent that the reservoir chamber 3 contains main line pressure of air, which together with the expansive force of the spring 38 5 retains the valve 40 seated or closed, and it is this supply of air in the reservoir that is trapped therein for working requirements as will appear in the final or extreme adjustment of the valve. To completely open 10 the jaws of the chuck, the handle 8 of the movable valve member 7 is shifted to a position of approximately one hundred and five degrees from its original position, thus placing the groove 12^a of the angle port 12 in 15 the position shown in Fig. 4. The groove 12^a of the angle port 12 will establish communication between the reservoir 3 and the pipe F through ports 21, groove 12^a and port 22, thereby charging the chamber B of the work 20 cylinder C. The groove 13^a of the angle port 13 will establish communication between the pipe G and ports 23 and 24, thereby permitting the chamber A to exhaust to the atmosphere. The piston D is reciprocated by the 25 pressure of air within the chamber B and the jaws of the chuck are completely opened. 30

Now, should the pressure of air within the reservoir chamber 3 be reduced through communication being established between 35 the reservoir chamber 3 and chamber B of the work cylinder and the air expanding to a larger volume or to a point where the combined pressure of air in reservoir chamber 3 and expansive pressure of spring 38 40 are less than air pressure on exposed area of valve 40 in port 41, the valve 40 will be unseated admitting the main line pressure of air to the reservoir chamber 3 to perform the duty required of the valve at this position of the member 7.

As before stated, working requirements or conditions may be encountered where the pressure of air within the reservoir chamber 3 is not sufficient to expeditiously 50 accomplish a desired result. As an instance of a working requirement, the cylinder C may be of considerable length, and so also, the travel of the piston D. As this piston D was left in close proximity to the end wall 55 of the cylinder C, the greater part of the air pressure within the reservoir chamber may be utilized in starting the piston D away from the end wall of the cylinder, and with the greater part of the air pressure expended 60 in this effort, the remaining pressure of air, as originally provided for in the four-way valve, may not be sufficient to shift the piston D throughout its predetermined path of travel. It may complete its journey but at 65 a very slow speed, so to insure quick travel

and a positive operation of the valve, the main pressure is utilized as a reserve force to accomplish any work that cannot be performed by the air pressure stored within the reservoir chamber 3. The valve 40 can 70 therefore be rightly considered as a pressure building valve, as such valve is only unseated, to increase the air pressure within the reservoir 3, when the pressure therein drops below a working condition. The 75 spring 38 associated with the valve 40 is therefore of less expansive force or pressure than the main line pressure of air, so that when the pressure of air within the reservoir chamber 3 is reduced, and together 80 with the pressure of the spring 38 falls below the main line air pressure, then the valve 40 will unseat and establish communication between the ports 11 and the chamber B of the cylinder C.

There is little, if any, likelihood of leakage due to the construction of the valve but should there be any serious undiscovered leakage in cylinder C or its connections, the main line pressure of air will insure a working 85 charge in the cylinder.

By removing the plug 37 the abutment 36 may be adjusted to regulate the expansive force of the spring 38 relative to the valve 40.

It is thought that the operation and utility 90 of my improvement will be apparent without further description, and while in the drawing there is illustrated a preferred embodiment of my invention, it is to be understood that the structural elements are susceptible to such variations and modifications 100 as fall within the scope of the appended claims.

What I claim is:

1. A four-way valve comprising a valve 105 body adapted to receive a main line pressure of air, a reservoir chamber adapted to communicate with said valve body to receive air therefrom, a rotary ported valve member carried by said valve body and 110 adapted to admit air to said reservoir chamber from said valve body, and an automatic valve in said reservoir chamber adapted to admit air thereto independent of said rotary ported valve member.

2. A four-way valve as characterized in 115 claim 1, and wherein adjustable means regulates the action of said automatic valve.

3. A four-way valve comprising a valve 120 body adapted to receive a main line pressure of air, a reservoir chamber adapted to communicate with said valve body and receive air therefrom, adjustable means adapted to establish communication between said valve body and said reservoir chamber 125 to conduct and trap a charge of air therein at the same pressure as the main line pressure of air, and means carried by said reservoir chamber adapted to establish communication between said reservoir chamber and 130

said valve body to replenish said charge of air when the pressure thereof falls below the main pressure of air.

4. A valve as characterized in claim 3, and wherein said means includes a spring 5 pressed pressure building valve.

5. The combination of a work cylinder, a piston therein, a valve body communicating with the ends of said work cylinder, and 10 with the main line pressure of air, an adjustable valve member carried by said valve body and having ports therein constructed and arranged in one position of said valve member to permit air entering one end of 15 said cylinder to shift said piston, and exhaust from the opposite end of said cylinder, in another position to permit of air being stored in the reservoir and equalized at the sides of said piston, and in another position 20 to permit of the stored air entering one end of said cylinder and the opposite end thereof exhausting, and means adapted to establish communication between the main line pressure of air and the stored air to 25 replenish and increase the pressure of stored air.

6. The combination as set forth in claim 5, and wherein the additional means is in the form of an automatic valve capable of 30 having its action regulated.

7. A four-way valve comprising a valve body adapted to receive a main line pressure of air, a reservoir chamber adapted to communicate with said valve body and receive air therefrom, adjustable means adapted to establish communication between said valve body and said reservoir chamber to conduct and trap a charge of air therein at the same pressure as the main line pressure of air, and means carried by said reservoir chamber adapted to establish communication between said reservoir chamber and 40

said valve body to replenish and build up the pressure of said charge of air when the pressure thereof is suddenly reduced and 45 falls below an adjustable and predetermined pressure owing to communication being established by said means between said reservoir chamber and an outlet port in the valve body of said four-way valve. 50

8. The combination of a work cylinder, a piston therein, a valve body communicating with the ends of said work cylinder and with a main line pressure of air, an adjustable valve member carried by said valve body and having ports therein constructed and arranged in one position of said valve member to permit air entering one end of said cylinder to shift said piston, and exhaust from the opposite end of said cylinder, in another position to permit of air being admitted to a reservoir chamber and in the same position permitting the pressure of air in the chambers on each side of said piston to be equalized by communication being established between the said chambers of the work cylinder through said valve body and said ported adjustable valve member and in another position to permit the air stored in the reservoir chamber to enter at one end of said work cylinder and the other end to exhaust, and means adapted to establish communication between the main line pressure of air and the air admitted to and stored in the reservoir chamber to replenish and increase the pressure of air in the said reservoir chamber. 65

In testimony whereof I affix my signature in the presence of two witnesses.
